UNITED STATES PATENT OFFICE.

THOMAS CORDINGLEY, OF BRISTOL, ENGLAND, ASSIGNOR TO MARY CREASE SEARS, OF BOSTON, MASSACHUSETTS.

SPRING GAITER.

Application filed August 29, 1925. Serial No. 53,311.

To all whom it may concern:

Be it known that I, THOMAS CORDINGLEY, a subject of the King of Great Britain and Ireland, residing at 386 Hotwell Road, Bristol, in the county of Gloucestershire, England, have invented a new and useful Spring Gaiter, of which the following is a specification.

My invention relates to an improved construction of gaiter for the springs of motor and other vehicles, and is of the type in which an outer sheath or cover is shaped to fit snugly round the leaf springs of the motor or other vehicle so as to retain suitable lubricant around the springs and to exclude dirt and grit therefrom.

According to this invention, my improved gaiter comprises an inner tray or retainer for the lubricant adapted to fit under the leaf spring and up the sides thereof. This tray is preferably of substantially channel shape and may be deeper at one end than the other so as to fit the usual form of spring which tapers from the centre outwardly. This tray may be formed of leather, fibre or other suitable flexible material and is moulded to the desired form so as to fit closely to the shape of the spring. In each end of the tray is provided a suitable lubricant retainer in the form of a strip of soft material such as felt, which may extend completely round the spring and serves to prevent the escape of the lubricant from the ends of the tray. The tray for the lubricant is held in position and enclosed by an outer sheath of leather or other suitable material preferably formed in one piece and moulded to fit closely round the spring and the tray. A suitable longitudinal joint is provided along its underside so as to permit it to be opened for placing in position round the spring. Suitable means such as tags and lacings may be provided along the two edges of this joint to enable

them to be secured together when the outer sheath is placed in position. For this purpose, a pair of strips of metal or other suitable material may be secured one along each edge of the joint in the outer sheath. These strips are provided with a series of projecting tags or hooks around which a leather or other lace may be engaged and when drawn tight will hold the two edges of the joint closely together. It is preferred to employ rustless steel strips hav-

ing the desired projections or hooks formed thereon by stamping or other suitable means. These strips may be attached to the edges of the outer sheath of the gaiter by means of a leather or other strip placed over them and provided with small holes through which the hooks project. Each leather or other strip is secured to the substance of the outer sheath of the gaiter by sewing or other suitable means.

Around each end of the outer sheath of the gaiter is provided a suitable strap having a buckle or other suitable means by which it may be drawn tight to compress the end of the gaiter round the spring. This will also hold the strip of packing material provided in the tray tightly against the spring and will thus assist in preventing the escape of the lubricant or the ingress of dirt and wet.

Both the inner tray for the lubricant and the outer sheath of the gaiter are shaped to conform closely to the contour of the spring and suitable bulges or recesses may be formed to accommodate spring clips or other projections on the springs. It is preferred to employ leather for the tray and the outer sheath but other suitable material may be used if desired. Owing to the outer sheath being made in one piece with a single longitudinal joint on its underside and the provision of the internal tray which completely covers this joint and retains the lubricant my improved gaiter is substantially watertight and effectively retains the lubricant around the spring so that it will be kept in perfect condition and will operate under the best possible circumstances.

In order that my invention may be clearly understood, reference is made to the accompanying drawings, in which:—

Fig. 1 is a perspective view of a spring gaiter constructed according to my invention.

Fig. 2 is a perspective view of the internal tray removed from the gaiter.

Fig. 3 is a perspective view of one end of the gaiter shown in an inverted position so as to show clearly the method of lacing up the outer casing, and

Fig. 4 is a transverse section through the gaiter showing the tray in position.

Referring to the drawings, the gaiter comprises an inner tray 1 of U-shape deep at the end 2 and shallow at the end 3 so as to

conform to the shape of the usual leaf-springs employed upon motor vehicles. The tray is moulded to shape from stout leather of good quality which has been suitably rendered grease and water proof by any convenient process such for instance as by impregnating it with carnauba. The sides of the tray are pressed outwardly at 4 on each side to accommodate the bolt of the spring 10 clip which is usually employed for retaining the leaves of the spring in correct alignment. These portions 4 are pressed out during the moulding operation. In both ends 2 and 3 of the tray is provided a grease retaining strips 5 and 6 respectively secured as shown by rivets 7. The free ends 8 of the strips 5 and 6 are arranged to wrap over the top of the springs after the tray has been placed in position.

20 The outer sheath 10 is of special quality leather rendered grease and water proof by a suitable process such as impregnation with carnauba wax and moulded to the shape shown in Fig. 1. The outer sheath 10 is 25 rectangular in section and tapers from end to end as shown so as to correspond with the shape of the spring. The joint between the edges 11 of the sheath is arranged along the centre line of the underside of the 30 spring and thus runs centrally along underneath the tray 1 which the sheath fits round is shown in Fig. 1. The sheath 10 is moulded with an enlarged portion 12 at a suitable position to accommodate the spring clip and 35 the projections 4 in the tray which engage round the ends thereof. The two edges 11 which meet along the centre of the undersurface thereof are suitably reinforced by covering strips 14 which enclose spring steel strips 40 15 having hooks 16 thereon which project through holes in the reinforcing strips 14. A suitable leather or other lace 17 is engaged round these hooks 16 so as to secure the two edges of the sheath closely together.

45 At both ends of the sheath is provided a strap 18 passing through slots 19 in the sides of the sheath and over and under the top and bottom thereof. These straps are secured by suitable buckles so as to draw the 50 ends of the sheath tightly round the springs to which they are fitted. This will force the packing strips 5 and 6 in the ends of the tray 1 closely against the outer surface of the 55 springs so as to effectively retain the lubricant inside the gaiter and at the same time to exclude wet and dirt from the springs.

My improved gaiter may be readily placed in position and gives a neat and smart finish to the springs. It may be easily removed and replaced and will retain its shape and effectiveness over a very long period.

I claim:

1. In spring gaiters for the springs of motor and other vehicles, a U-shaped tray 60 to engage under the spring, an outer sheath

to engage over the spring and tray when in position on the spring and a longitudinal joint in the outer sheath, arranged along its underside and beneath the tray.

2. In spring gaiters for the springs of 70 motor and other vehicles, a U-shaped tray of leather impregnated with carnauba wax and moulded to shape under pressure to engage under the spring, an outer sheath to engage over the spring and tray when in 75 position on the spring and a longitudinal joint in the outer sheath, arranged along its underside and beneath the tray.

3. In spring gaiters for the springs of 80 motor and other vehicles, a U-shaped tray to engage under the spring, an outer sheath of leather impregnated with carnauba wax and moulded to shape under pressure to engage over the spring and tray when in 85 position on the spring, and a longitudinal joint in the outer sheath, arranged along its underside and beneath the tray.

4. In spring gaiters for the springs of 90 motor and other vehicles, a U-shaped tray of leather impregnated with carnauba wax and moulded to shape under pressure to engage under the spring, an outer sheath of leather impregnated with carnauba wax and moulded to shape under pressure to engage over the spring and tray when in 95 position on the spring and a longitudinal joint in the outer sheath arranged along its underside and beneath the tray.

5. In spring gaiters for the springs of 100 motor and other vehicles, a U-shaped tray to engage under the spring, an outer sheath to engage over the spring and tray when in position on the spring, a longitudinal joint in the outer sheath arranged along its underside and beneath the tray, packing strips 105 in both ends of the tray to retain the lubricant and loose ends to these packing strips to wrap over the top of the springs.

6. In spring gaiters for the springs of 110 motor and other vehicles, a U-shaped tray of leather impregnated with carnauba wax and moulded to shape under pressure to engage under the spring, an outer sheath to engage over the spring and tray when in 115 position on the spring, a longitudinal joint in the outer sheath arranged along its underside and beneath the tray, packing strips in both ends of the tray to retain the lubricant and loose ends to these packing strips to 120 wrap over the top of the springs.

7. In spring gaiters for the springs of 125 motor and other vehicles, a U-shaped tray to engage under the spring, an outer sheath of leather impregnated with carnauba wax and moulded to shape under pressure to engage over the spring and tray when in position on the spring, a longitudinal joint in the outer sheath arranged along its underside and beneath the tray, packing strips in 130 both ends of the tray to retain the lubricant

and loose ends to these packing strips to wrap over the top of the springs.

8. In spring gaiters for the springs of motor and other vehicles, a U-shaped tray of leather impregnated with carnauba wax and moulded to shape under pressure to engage under the spring, an outer sheath of leather impregnated with carnauba wax and moulded to shape under pressure to engage over the spring and tray when in position on the spring, a longitudinal joint in the outer sheath arranged along its underside and beneath the tray, packing strips in both ends of the tray to retain the lubricant and loose ends to these packing strips to wrap over the top of the springs.

9. In spring gaiters for the springs of motor and other vehicles, a U-shaped tray to engage under the spring, an outer sheath to engage over the spring and tray when in position on the spring, a longitudinal joint in the outer sheath arranged along its underside and beneath the tray, reinforced edges to the longitudinal joint of the sheath, spring strips in the reinforced edges and hooks on these strips for the engagement of laces to connect the two edges securely together and retain the gaiter in position.

10. In spring gaiters for the springs of motor and other vehicles, a U-shaped tray of leather impregnated with carnauba wax and moulded to shape under pressure to engage under the spring, an outer sheath to engage over the spring and tray when in position on the spring, a longitudinal joint in the outer sheath arranged along its underside and beneath the tray, reinforced edges to the longitudinal joint of the sheath, spring strips in the reinforced edges and hooks on these strips for the engagement of laces to connect the two edges securely together and retain the gaiter in position.

connect the two edges securely together and retain the gaiter in position.

11. In spring gaiters for the springs of motor and other vehicles a U-shaped tray to engage under the spring, an outer sheath of leather impregnated with carnauba wax and moulded to shape under pressure to engage over the spring and tray when in position on the spring, a longitudinal joint in the outer sheath arranged along its underside and beneath the tray, packing strips in both ends of the tray to retain the lubricant, loose ends to these packing strips to wrap over the top of the springs, reinforced edges to the longitudinal joint of the sheath, spring strips in the reinforced edges and hooks on these strips for the engagement of laces to connect the two edges securely together and retain the gaiter in position.

12. In spring gaiters for the springs of motor and other vehicles, a U-shaped tray of leather impregnated with carnauba wax and moulded to shape under pressure to engage under the spring, an outer sheath of leather impregnated with carnauba wax and moulded to shape under pressure to engage over the spring and tray when in position on the spring, a longitudinal joint in the outer sheath arranged along its underside and beneath the tray, packing strips in both ends of the tray to retain the lubricant, and loose ends to these packing strips to wrap over the top of the springs, reinforced edges to the longitudinal joint of the sheath, spring strips in the reinforced edges and hooks on these strips for the engagement of laces to connect the two edges securely together and retain the gaiter in position.

THOMAS CORDINGLEY.
